UNITED STATES PATENT OFFICE

HERMAN G. BLOSSER, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed May 22, 1929. Serial No. 365,181.

My invention relates to railway traffic controlling apparatus, and particularly to apparatus of the type involving means for supplying periodically interrupted alternating current to the track rails, and governing mechanism on the train responsive to such periodically interrupted current. More particularly the present invention relates to the trackway portion of such apparatus.

10 I will describe one form of apparatus embodying my invention, and will then point out the novel features thereof in claims.

In the accompanying drawing, Fig. 1 is a diagrammatic view showing the trackway portion of one form of system embodying my invention. Fig. 2 is a view showing one form of code transmitter indicated diagrammatically in Fig. 1 and also embodying my invention.

20 Similar reference characters refer to similar parts in each of the views.

Referring first to Fig. 1, the reference characters 1 and 1^a designate the track rails of a stretch of railway track along which traffic normally moves in the direction indicated by the arrow. These rails are divided by insulated joints 2 into track sections, of which only one section A—B is shown in the drawing. This section is provided with a 25 track circuit comprising a track battery 6 normally connected across the rails at the exit end of the section, and a track relay T^A connected across the rails at the entrance end of the section. Section A—B is also provided with a code transmitter designated by the reference character CT, which transmitter is illustrated more fully in Fig. 2.

Referring to Fig. 2, the code transmitter comprises a spring motor M operatively connected through the medium of gearing 12 with a contact operating cam 4 and also with an alternating current generator G. Also connected with the spring motor M is an escapement device E comprising a drum 13, the 40 periphery of which is provided with a plurality of wings 14, 14^a, 14^b, etc., alternately slanted in opposite directions with respect to the axis of the drum, and alternately terminating a short distance from the right and 45 left-hand faces of the drum respectively.

Co-operating with the escapement device E is a pendulum P pivotally mounted at 15 and having a tongue 16 located in the path of the wings 14. As the pendulum swings in clockwise direction from the position in 55 which it is shown in the drawing, the tongue 16 will move to the right out of the path of the wing 14 and thereby allow the drum 13 to rotate through a small angle until the next wing 14^a engages the tongue 16. Due 60 to the slope of this wing with respect to the axis of the drum, the pendulum will be urged to swing in counter-clockwise direction until the tongue 16 is released by the left-hand end of the tongue 14^a. Assuming that the pendulum is free to swing, this process will be 65 repeated indefinitely, with the result that the speed of operation of the spring motor M will be regulated by the natural period of oscillation of the pendulum P. The device 70 is provided with an electromagnet 3, which, when energized, holds the pendulum at one end of its stroke and thereby holds the spring motor and the parts connected therewith at rest. An electric motor 11 may be provided 75 for keeping the spring motor M fully wound, the electric motor 11 being controlled by the spring motor in the usual and well known manner, whereby when the spring motor becomes unwound to a certain extent, the electric motor will be energized to rewind the 80 spring motor.

Again referring to Fig. 1, the code transmitter CT is controlled by a coder relay C, which in turn is controlled by the track relay T^A. The circuit for the coder relay C includes a back contact 8 of relay T^A, so that relay C is normally de-energized but becomes energized 85 when a train enters section A—B.

When the section A—B is unoccupied, so 90 that relay C is de-energized, the code transmitter is held at rest by a circuit which passes from terminal B of a suitable source of current, through back contact 9 of relay C and the winding of magnet 3 to terminal O of the same source of current. At the same time track battery 6 is connected with the track rails of the section through the back point of contact 10 of relay C. When a train enters 95 section A—B, it opens track relay T^A, there- 100

by energizing relay C, and the opening of back contact 9 of the latter relay de-energizes magnet 3, so that pendulum P is released and the code transmitter CT is set into operation. If track relay T^a for the section next in advance of section A—B is energized, generator G is connected with the rails of section A—B through a contact 5 operated by the cam 4, the circuit being from the left-hand terminal of generator G, through the front point of contact 10 of relay C, battery 6, to the lower rail 1^a, and from the upper rail 1 through front contact 7 of track relay T^a and contact 5 of the code transmitter to the right-hand terminal of generator G. The alternating current furnished by the generator G is therefore periodically interrupted by the contact 5, and this periodically interrupted current is supplied to the rails of section A—B for the control of the train which occupies the section. When the train leaves the section, track relay T^a again becomes energized, so that the coder relay C becomes de-energized, with the result that magnet 3 is energized to stop the code transmitter, and generator G is disconnected from the track rails.

As shown in Fig. 1, the code transmitter is provided with only one cam 4 and co-operating contact 5, although in actual practice any desired number of cams and contacts may be provided for periodically interrupting the alternating current at different frequencies, the contacts being selectively connected with the track rails in accordance with traffic conditions in advance.

Although I have herein shown and described only one form of apparatus embodying my invention, it is understood that various changes and modifications may be made therein within the scope of the appended claims without departing from the spirit and scope of my invention.

Having thus described my invention, what I claim is:

1. A code transmitter comprising a spring motor, an alternating current generator driven by said motor, and means also driven by said motor for periodically interrupting the output current of said generator.
2. A code transmitter comprising a spring motor, means including a pendulum for regulating the speed of said motor, an alternating current generator driven by said motor, and means also driven by said motor for periodically interrupting the output current of said generator.
3. A code transmitter comprising a spring motor, an electric motor for winding said spring motor, an alternating current generator driven by said spring motor, and means operated by said spring motor for periodically interrupting the output current of said generator.
4. A code transmitter comprising a spring

motor, an electric motor for winding said spring motor, means including a pendulum for regulating the speed of said spring motor, an alternating current generator driven by said spring motor, and means operated by said spring motor for periodically interrupting the output current of said generator.

5. A code transmitter comprising a spring motor, means including a pendulum for regulating the speed of said motor, means for retaining said pendulum at one end of its stroke to stop the operation of said motor, an alternating current generator driven by said motor, and means also driven by said motor for periodically interrupting the output current of said generator.

6. A code transmitter comprising a spring motor, an escapement device operatively connected with said motor, a pendulum co-operating with said escapement device to regulate the speed of said motor, means for retaining said pendulum at one end of its stroke to hold said motor at rest, an alternating current generator driven by said motor, and means also driven by said motor for periodically interrupting the output current of said generator.

7. In combination, a section of railway track, a spring motor, an alternating current generator operatively connected with said motor, a contact, means operated by said motor for periodically opening and closing said contact, an escapement device operatively connected with said motor, a pendulum co-operating with said escapement device to regulate the speed of said motor, a normally energized magnet for retaining said pendulum at one end of its stroke to hold said motor at rest, and means responsive to a train entering said section for opening the circuit of said magnet to release said pendulum and connecting said generator with the rails of said section through said contact.

In testimony whereof I affix my signature.

HERMAN G. BLOSSER.
